UNITED STATES PATENT OFFICE.

HENRY GUSTAV ALBRECHT AND CHRISTIAN NIELSON, OF WAHPETON,
DAKOTA TERRITORY.

PAD-TREE FOR HARNESS.

SPECIFICATION forming part of Letters Patent No. 284,160, dated September 4, 1883.

Application filed December 19, 1882. (No model.)

To all whom it may concern:

Be it known that we, HENRY GUSTAV ALBRECHT, a subject of the Emperor of Germany, and CHRISTIAN NIELSON, a subject of the King of Denmark, both having declared their intention of becoming citizens of the United States, and both residing at Wahpeton, in the county of Richland and Territory of Dakota, have jointly invented certain new and useful Improvements in Swiveled Pad-Trees for Harness, of which the following specification is a full, clear, and exact description, reference being also had to the accompanying drawings, in which—

15 Figure 1 is a semi-sectional front elevation, Fig. 2 is a side elevation, and Fig. 3 is a plan view, of a portion of a pair of pads with our improved swiveled tree arranged thereon. Figs. 4, 5, and 6 are perspective views, enlarged, of the metal portions of the device.

20 This invention is intended to be applied to the metal trees connecting the pads of the saddle; and it consists in the construction hereinafter particularly described, and then sought to be specifically defined by the claim.

25 As illustrated in the accompanying drawings, the metal plates A are embedded within the pads B' B² and provided with two ears, a' a², projecting from each of the metal plates A out through the covering of the pads B' B². By this means the ears a' a² only show outside the pads, the plates being entirely concealed and secured within the pad by rivets, sewing, or in any other suitable manner. Swiveled 30 by its ends, between each pair of the ears a' a², is a curved metal "tree," C, to which the check-rein hook b, and rein-terrets c, and crupper or back-strap loop d are attached. By this means the pads B' B² are movable upon the 35 pins of the ears a' a², so that they will adjust themselves to the back of the horse, no matter of what shape or size, and thus avoid chafing or rubbing, or bearing unequally. By this

arrangement one set of pads will fit all forms or sizes of horses; hence no change of harness need be made for different-sized horses, but one harness may be used for all sizes. Pivoted upon the outer ends of the same pins that hold the tree C, between the ears a' a², are two metal loops, e' e², in which the back-bands or bearing-straps D are secured, these straps passing through the ordinary loops, g' g², on the pads B' B². This is the form used on single harness; but the same swiveled tree may of course be used equally well on double harness.

45 All the metal parts will usually be of malleable iron, and all the exposed portions will be plated with silver, nickel, gold, or galvanized or finished in any other well-known manner.

50 By having the ends of the trees C fit between the ears a' a² and the ends of the loops e' e² outside of the ears the latter are braced and strengthened; but while we consider the method just described the best method, and desire to be protected therein, yet we do not want to be confined thereto.

55 Having described our invention and set forth its merits, what we claim is—

The combination of the pad-plates A A, secured under the pad-covering, and having ears a' a² projecting upward through the covering, the metallic tree C, pivoted between the said ears, and the back-band loops e' e², pivoted by the same pins outside of the same ears, substantially as and for the purpose herein specified.

60 In testimony whereof we have hereunto set our hands in the presence of two subscribing witnesses.

HENRY GUSTAV ALBRECHT.
CHRISTIAN NIELSON.
